(57) **CLAIM**

The ornamental design for a board game for two participants with pieces and board, as shown and described.

DESCRIPTION

FIG. 1 is a perspective view of the board game for two participants with pieces and board of my design;

FIG. 2 is a top plan view of the board only of my design;

FIG. 3 is a bottom plan view of the board only of my design;

FIG. 4 is a left side perspective view of my design, with the right side perspective view being the same;

FIG. 5 is a front perspective view of my design, with the rear perspective view being the same;

FIG. 6 is a left side elevational view of the board of my design, with the right side elevational view being the same;

FIG. 7 is a front elevational view of the board of my design, with the rear elevational view being the same;

FIG. 8 is a front elevational view of the plurality of the playing pieces, for use on one side of the board;

FIG. 9 is a perspective view of one playing piece of my design;

FIG. 10 is a front elevational view of the playing piece of FIG. 9;

FIG. 11 is a rear elevational view of the playing piece of FIG. 9;

FIG. 12 is a left side elevational view of the playing piece of FIG. 9;

FIG. 13 is a right side elevational view of the playing piece of FIG. 9;

FIG. 14 is a bottom plan view of the playing piece of FIG. 9; and,

FIG. 15 is a top plan view of the playing piece of FIG. 9.
